UNITED STATES PATENT OFFICE.

JOSEPH DOTY, OF WELLSVILLE, NEW YORK.

ANTI-RATTLER FOR THILL-COUPINGS.

SPECIFICATION forming part of Letters Patent No. 425,867, dated April 15, 1890.

Application filed August 28, 1889. Serial No. 322,219. (No model.)

To all whom it may concern:

Be it known that I, JOSEPH DOTY, a citizen of the United States, and a resident of Wellsville, in the county of Allegany and State of New York, have invented certain new and useful Improvements in Anti-Rattlers for Thill-Couplings; and I do hereby declare that the following is a full, clear, and exact description of the invention, which will enable others skilled in the art to which it appertains to make and use the same.

This invention relates to improvements in anti-rattlers for thill-couplings.

Heretofore it has been proposed to make the anti-rattler of rubber or to employ a coiled spring, and it has been found by experience that the rubber soon becomes, by reason of its exposure to the weather, hardened and non-elastic, and consequently useless, as also the spring for the same reason.

The leading object of my invention is the production of an anti-rattler, which will form a perfect cushion for the draw-iron, and will receive and withstand the pressure brought to bear upon the anti-rattler, and also withstand the damaging influence of the weather.

A further object of the invention is the production of a device which can be applied to any thill-coupling quickly and with ease, and which may be produced at a very low cost.

To attain the desired object the invention consists of an elastic block or cushion adapted to be inserted between the shackle and draw-iron, and containing and holding in place a coiled-wire spring, which bears normally upon the said shackle and draw-iron.

In the accompanying drawings, forming part of this specification, and in which like letters of reference indicate corresponding parts, Figure 1 represents a perspective view of a thill-coupling with my anti-rattler applied. Fig. 2 represents a perspective view of the anti-rattler detached, and Fig. 3 represents a longitudinal sectional view thereof.

The anti-rattler consists of a rubber or elas-

tic block or cushion A, having a coiled-wire spring B, placed therein in such a manner that the ends bear against the thill and draw-iron. In this instance the cushion is formed with a bore or passage C to receive the spring. 50

The device is placed in position, as shown in the drawings, and the draw-iron exerting pressure against the spring compresses the same, and the compressing of the spring causes it to form a firm cushion for the draw-iron, thereby effectually preventing all rattling and resisting the force or strain brought to bear thereon.

Having thus described my invention, what I claim as new, and desire to secure by Letters 60 Patent, is—

1. An anti-rattler consisting of a rubber or other elastic block provided with a longitudinal bore, in combination with a coiled spring passing entirely through said bore, substantially as set forth. 65

2. An anti-rattler consisting of an elastic cushion having a bore therein, and a compound spring arranged in said bore, substantially as and for the purpose described. 70

3. In an anti-rattler for thill-couplings, the combination, with a shackle provided with the usual forwardly-extending ears, a draw-iron pivoted between said ears, of an elastic cushion disposed between the ears of the 75 shackle, said cushion provided with a longitudinal bore having its front face concave to fit against the periphery of the draw-iron eye, in combination with a coiled spring passing through said bore, one end thereof pressing 80 against the rear of the shackle and the opposite end against the periphery of the draw-iron, substantially as set forth.

In testimony that I claim the foregoing as my own I have hereunto affixed my signature 85 in presence of two witnesses.

JOSEPH DOTY.
